APPARATUS FOR SANDING HIGHWAYS

Filed Dec. 20, 1939

UNITED STATES PATENT OFFICE

2,303,876

APPARATUS FOR SANDING HIGHWAYS

Roy Gaddis, Davenport, Iowa

Application December 20, 1939, Serial No. 310,164

7 Claims. (Cl. 275—8)

This invention relates to sand distributing machines and particularly to a means for and method of evenly and effectively distributing sand and the like on the surfaces of roadways and making it stick to such surfaces.

It has become common practice during the last few years to spread sand, cinders or other abrasive material over icy streets and highways to help eliminate some of the dangers of driving during icy weather. Frequently such materials are distributed by hand, as by shoveling it out of a moving truck. This is, of course, a very inefficient method of distribution as the sand is lumpy and the worker cannot distribute it in the even, widely distributed pattern necessary for uniform, efficient sanding.

Several types of mechanical sanders have been proposed but I have found that most of these have no means for regulating accurately the quantity of sand distributed. For instance, an intersection might require much heavier sanding than a level highway.

It is, therefore, a primary object of my invention to provide an improved device for distributing sand or other substances of the like, and for regulating the amount to be distributed.

I have also noted that with any of the methods so far advanced for distributing anti-skid materials on paving, and particularly in the coldest weather, the materials do not cling to the surface of the ice due to the extreme hardness of the ice. I have noticed that, in the coldest weather, the sand or other grit is usually swept aside by passing cars, particularly in an area where the cars suddenly increase their speed or apply their brakes.

It is, therefore, another important object of my invention to provide, in such a sand distributing device, a method of treating the sand by heating it as it is fed through the machine. The heated sand thus fed from the device will not only be dry and free of lumps, but will partly embed itself in the ice covering the street to not only give better traction to cars passing over the icy pavement, but also to prevent the grit from being swept out of place.

Other and further features and objects of the invention will be more apparent to those skilled in the art upon a consideration of the accompanying drawing and following specification, wherein are disclosed several exemplary embodiments of the invention, with the understanding, however, that such changes may be made therein as fall within the scope of the appended claims,

without departing from the spirit of the invention.

In said drawing:

Figure 1 is a view in elevation representing a sand distributing device constructed according to one embodiment of my invention, and partly broken away to better illustrate its structure.

Figure 2 is a view in end elevation of the device shown in Figure 1 taken along the line 2—2 partially broken away to illustrate the structure, and

Figure 3 is a view in section of the device shown in Figure 1 as taken along the lines 3—3.

Referring now to the drawing and more particularly to Figures 1 to 3, a device is there illustrated which is constructed in accordance with one embodiment of my invention.

In the form of the device shown in Figures 1 to 3 inclusive, means are provided for accurately regulating the quantity of sanding material fed through the machine. A structure constructed according to this modification of my invention includes a main frame 55 adapted to be supported upon the rear end of a vehicle, a sand hopper 56, a sand distributor 57, a drive means such as a gas engine 58, a speed reduction drive 59 for the distributor shaft 61, heater means 62, and a conveyor for conveying sand from the hopper to a point above the distributor means. The sand is carried in the vehicle box and loaded by hand into the hopper 56.

Sand from the hopper is fed onto conveyor 63 which carries the sand through the heater chamber 64 and discharges it at a point within the casing 66 and above the distributing wheel 57. The conveyor 63 is preferably in the form of a pair of chains 67 having a large number of drag bars 73 adapted to rest on the drag plate 74. The chains are supported on sprockets 68 and 69 which are in turn mounted for rotation on cross shafts 71 and 72.

The cross shaft 72 is preferably driven at a speed considerably below that of the vertical distributor shaft 61. The drive may be accomplished, as shown, by means of a worm on the distributor shaft and a worm gear on the cross shaft or by any other suitable means such as a pair of bevel gears enclosed in the upper gear case 59 in addition to the main reduction gearing. If this last mentioned method is used, one bevel gear may be mounted on the vertical shaft 61 to drive the other bevel gear on a short cross shaft from which power may be transmitted by means of a pulley mounted on the short cross shaft through a V-belt to another larger pulley mounted on the sprocket drive shaft 72. It will be ap-

parent that, with such construction, it will be a simple matter to vary the rate of speed of the conveyor relative to the speed of the distributor by simply changing the sizes of pulleys and belt.

The conveyor itself may comprise either a plurality of drag bars 73 attached at spaced intervals along each conveyor chain and adapted to drag the sand along the top of the drag plate 14 to a point above the discharge end of the casing 66, or the conveyor may be made in substantially belt-like form by attaching a flat plate-like member to each link of the chain and mounting them so as to be closely adjacent to one another so as to form a practically continuous surface.

The amount of grit sent through the machine may be regulated in any case by means such as shown at 76. This may comprise a small hopper member adapted to receive material from the main hopper 56. This small hopper may be hingedly mounted on one side, as shown at 77, and supported on the opposite side by adjustable means such as the rod 78 and the wing nut 79, to permit adjustment of the spacing between the bottom of the hopper and the top of the conveyor chain. Of course any other suitable means for varying the spacing of the effective lower edge of the hopper with the conveyor belt may be used.

When it is desired to feed only a small quantity of sand through the device, the small hopper 76 is lowered to permit it to barely clear the drag bars of the conveyor chain, and when a heavier feed is desired, the wing nut 79 is screwed downward to lift the small hopper and thus permit sand to be deposited on the conveyor to a greater depth.

A sliding valve 81 may be provided in the bottom of the main hopper, if desired, to completely shut off the flow of sand downwardly through the hopper. This sliding valve may be operated by means of a connecting rod 82, a bell crank 83, a vertical connecting rod 84, and an operating handle 85.

It will be noted that an outer heat retaining casing 86 is provided to at least partially enclose the hopper 56. This outer casing may be connected at its lower end to the heater chamber 64 and may be spaced away from the sand hopper, near the top edge thereof, to permit the outward passage of the burned gases, or the outer casing 86 may be provided near its upper edge with a plurality of openings 87 to serve the same purpose.

It is, of course, apparent that devices such as that here described may be applied to other uses than that of sanding icy streets. Such a device would be particularly suitable in evenly distributing sand over black top roads or newly tarred paving, which operations are generally performed manually.

It will be apparent that I have not only provided means for accurately regulating the quantity of sand or other grit passing through a distributing device, but have also provided a method and means for causing the grit to adhere to the icy surface of a street.

Although I have described a specific embodiment of my invention, it is apparent that modifications thereof may be made to those skilled in the art. For example, the sand may be heated before it is measured out for distribution or it may be heated as it is dropped off the conveyor. It will be apparent also that the abrasive may be passed over a heated plate rather than through

a heated chamber. Furthermore, means of heating other than the gasoline torch herein described may be used. These and other modifications may be made without departing from the spirit and scope of the invention as set forth in the appended claims.

I claim as my invention:

1. An abrasive material distributing device including a hopper, a distributor, a heater chamber, a conveyer for feeding abrasive through the heater chamber, means for depositing abrasive from the hopper onto the conveyer, means for regulating the depth of abrasive deposited, means for discharging material from the conveyer onto the distributor, and means for driving the distributor and the conveyer.
- 10 2. An abrasive material distributing device including a distributor, a hopper, a conveyer, means for discharging material from the hopper onto the conveyer, in a relatively thin layer, means for discharging material from the conveyer onto the distributor, means for enclosing the conveyer, and means for supplying heat to said enclosure for heating materials.
- 20 3. In a device for broadcasting anti-skid material, a distributor, a hopper, heater means, conveyer means for receiving material from the hopper and for feeding the material in a thin layer adjacent the heater means, and means for discharging the material thus heated onto the slinger.
- 25 4. In a device for broadcasting abrasives, a hopper, a distributor disc, a conveyer, means for driving the distributor disc and the conveyer, means for regulating the depth of discharge of abrasive on the conveyer, and means for discharging the abrasive from the conveyer onto the distributor disc.
- 30 5. In a device of the character described, a hopper, an enclosure for the hopper, a conveyer for receiving material discharged by the hopper, an enclosure for at least part of the conveyer, means for heating the space within the enclosure around the conveyer, and means for conducting some of the heat to the space within the enclosure around the hopper.
- 35 6. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the drag bars on the drag plate.
- 40 7. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.
- 45 8. In a device of the character described, a hopper, an enclosure for the hopper, a conveyer for receiving material discharged by the hopper, an enclosure for at least part of the conveyer, means for heating the space within the enclosure around the conveyer, and means for conducting some of the heat to the space within the enclosure around the hopper.
- 50 9. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.
- 55 10. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.
- 60 11. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.
- 65 12. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.
- 70 13. In a device of the character described, a hopper, a feed conveyor disposed therebelow, said conveyor including a drag plate and drag bars slidably disposed thereabove, a rotary disc distributor disposed below the discharge end of the conveyor drag plate, means for driving the said conveyor and distributor disc, and means for regulating the depth of material carried by the conveyor to the distributor disc, a casing enclosing at least the upper portion of said conveyor, and means for directing heat into said casing whereby material carried through said casing by the conveyor will be agitated by the said drag bars to thereby expose all of the material to the drying effect of the heat during its passage through said casing.

ROY GADDIS.
